H. L. YEATON

MANUFACTURE OF MOLDED COUNTER TURNED SHOES

Original Filed June 28, 1920

UNITED STATES PATENT OFFICE.

HARRY L. YEATON, OF BOSTON, MASSACHUSETTS, ASSIGNOR TO UNITED SHOE MACHINERY CORPORATION, OF PATERSON, NEW JERSEY, A CORPORATION OF NEW JERSEY.

MANUFACTURE OF MOLDED-COUNTER TURNED SHOES.

Application filed June 28, 1920, Serial No. 392,217. Renewed January 27, 1922. Serial No. 532,262.

To all whom it may concern:

Be it known that I, HARRY L. YEATON, a citizen of the United States, residing at Boston, in the county of Suffolk and State 5 of Massachusetts, have invented certain Improvements in the Manufacture of Molded-Counter Turned Shoes, of which the following description, in connection with the accompanying drawings, is a specification, 10 like reference characters on the drawings indicating like parts in the several figures.

This invention relates to the manufacture of turned shoes and is herein described in connection with the manufacture of a 15 turned shoe having a molded counter.

In the manufacture of such shoes it is desirable that the counter, particularly the forward portions of its wings, be reinforced in some way to prevent the wings from 20 spreading and the counter thereby losing the proper shape in the completed shoe; and hitherto various sorts of shape-retaining or reinforcing members have been employed, the common practice being to attach the 25 reinforcing member to the inturned flange of the counter and then to attach the counter to the sole, the principal difficulty encountered in carrying out the procedure being to locate the reinforced counter accurately 30 upon the sole prior to the attaching operation.

According to the present invention a portion of a component part of the shoe is used as a reinforcing or shape-retaining 35 member for the counter, such use serving not only to do away with the necessity for the extra reinforcing member hitherto commonly employed but in some cases to facilitate the proper locating of the counter. Conveniently 40 the heel end of the sole may be split by a cut parallel to the surface of the sole to produce a flap, and the inturned flange of the molded counter may be inserted in the slit beneath the flap and fastened to the 45 flap by any suitable means such as nails.

With such a procedure the flap, which is part of the sole, acts as a reinforcing member and its curved edge serves to locate the counter accurately in place.

Referring now to the accompanying drawings,—

Fig. 1 is a side elevation of the heel end of a sole which has been slit preparatory to incorporating it in a shoe having a Louis heel;

Fig. 2 is a perspective of the shoe as it appears on the first last, after the sewing operation has been completed and the counter placed in position;

Fig. 3 is a perspective of the heel end 60 of the shoe after it has been turned right side out and the shank stiffener fastened in place;

Fig. 4 is a perspective of the heel end of 65 the shoe after the second last has been inserted and the heel portion of the upper lasted over the edge of the counter;

Fig. 5 is a perspective of the heel end of 70 the shoe after the heel seat has been fitted, a Louis heel being shown in dotted lines;

Fig. 6 is a perspective of the heel end of 75 a sole prepared for incorporation in a shoe having a Cuban heel, the heel being shown in dotted lines;

Fig. 7 is a perspective of the heel end of 80 a sole prepared for incorporation in a shoe having a leather heel, the heel being shown in dotted lines, and

Fig. 8 is a perspective showing more particularly 85 the construction of the forward ends of the inturned flange of the molded counter and their relation to the sole.

Referring first more particularly to Figs. 1 to 5, with occasional reference to Fig. 8, the manufacture of a shoe having a Louis heel 90 will be described.

In Fig. 1, the heel end of a turn sole 9 is shown, the heel end being slit at two localities to form three flaps, a counter-reinforcing flap 11 adjacent the top or flesh side of the sole, a heel-seat flap 13 lying below it, and a heel-breast flap 15 adjacent the bottom or tread face of the sole. The sole slit in this manner, together with an assembled upper, which in the illustrated shoe 95 comprises an upper proper 17 and a lining 19, are placed wrong side out upon the first last 21, the lining being slit as shown

at about the heel breast line and its rear portion turned back out of the way. The upper and lining are then sewed as usual to the sole forwardly of a line in the vicinity 5 of the heel breast line. The inturned flange of a molded counter 23 is then inserted in the slit beneath the reinforcing flap 11 and fastened to the flap in the vicinity of the heel breast line in any suitable manner. 10 Conveniently an iron plate may be temporarily slipped beneath the counter flange and four nails 25, two on each side of the counter, driven through the flap and counter and clenched against the plate. When the 15 counter is placed in position and before the nails are driven, the counter is so manipulated, if necessary, that the curved edge of the heel end of the sole will contact with the inside wall of the counter, although a 20 molded counter is ordinarily so shaped and of sufficient resilience that merely pushing the counter lengthwise into place will accomplish this result.

It will be understood, that the heel end of 25 a sole which is designed for use with a wooden heel has approximately the outline of the insole pattern and that, consequently, when the counter has been fastened in position in the manner described above it is located with extreme accuracy. It should be noted, too, that the reinforcing flap 11 takes 30 the place of the reinforcing or shape-retaining member now commonly used, one purpose of which is to prevent the wings of 35 the counter from spreading in the completed shoe.

It is desirable in a turned shoe that the wings of the counter extend well forward but it is impractical to extend the slit by 40 which the flap 11 is formed much if any beyond the heel breast line. In case it is desired to use a counter of such length that it will extend well forward, the forward ends of its inturned flange may be slotted 45 transversely as shown at 27 and the extreme forward ends of the flange caused to overlie the sole as shown.

After the stage in the manufacture indicated in Fig. 2 has been reached, the heel 50 end of the shoe at that time being open, the first last 21 is pulled and the shoe turned right side out. During this turning the heel portion of the lining is carried up over the top and down inside the counter, its 55 lower margin being turned inwardly and laid down upon the inside of the sole, that is upon the top of the flap 11. A shank stiffener 29 which is coated on its under side with glue or similar material is then 60 placed in the shoe and fastened by one or more tacks, the shoe then being in the condition shown in Fig. 3. It will be noted that the shank stiffener lies on top of the forward ends of the inturned flange of the 65 counter, that by reason of the glue it ad-

heres to them as well as to the sole, and that the forward ends are thus fastened to the sole as well as to each other through the shank stiffener. This construction results in holding the wings of the counter 70 very firmly and preventing them from spreading.

The second last 31 is now inserted in the shoe and preferably two short transverse slits, one of which is shown at 33, are made 75 in the edge of the sole to facilitate the lacing of the heel portion of the upper. The heel seat flap is now lifted and the heel portion of the upper lasted over the counter and fastened by tacks 35, the shoe being 80 then in the condition shown in Fig. 4. The heel seat flap 13 is then laid and fastened by nails 37 so located as not to interfere with the heel seat fitting operation which follows. This latter operation is carried 85 out in the usual manner to provide a convex seat terminating forwardly in shoulders to provide a seat to fit into the cavity in a wooden heel. In the present case a Louis heel, indicated at 39 by dotted lines, 90 is attached and the heel breast flap 15 glued to the breast of the heel.

In case the shoe is to have a wooden heel other than a Louis heel, for example a Cuban heel, the manufacture of the shoe is carried out in the same manner except that no heel breast flap is provided. Referring to Fig. 6, the sole only of such a shoe is shown which is provided with a counter-reinforcing flap 211 and a heel-seat flap 213, the latter being shown after it has been fitted for the Cuban heel which is shown in dotted lines.

When a shoe having a leather heel is to be made the preparation of the sole is a 105 little different. When soles are died out for use in the manufacture of shoes having leather heels, the heel end of the sole does not correspond to the insole pattern. Instead it is considerably larger to provide an extension which may later be trimmed and finished. In case a shoe having a leather heel is to be made according to the present invention, when the sole is channeled, the lip cutting knife is thrown out at the proper time so as to make the usual lip, but the shoulder-forming knife is caused to run entirely around the heel end of the sole, and the slit by which the counter-reinforcing flap 311 and the heel-seat flap 313 are made 110 passes through the base of the shoulder. A sole so prepared is shown in Fig. 7, a leather-heel being shown in dotted lines. The manufacture of the shoe is the same as has been described above except in those 115 particulars in which the manufacture of a turned shoe having a leather heel always differs from that of a shoe having a wooden heel.

Although the invention has been set 120

forth in connection with a method of making a turned shoe in which a molded counter is attached while the shoe is wrong side out upon the first last, the component part 5 of the shoe upon which the flap is formed is the sole, and the heel end of the upper is left unlasted until after the shoe has been turned, it should be understood that the invention is not limited in the scope of the 10 application to the particular method or the particular shoe which has been shown and described.

Having thus described my invention, what I claim as new and desire to secure 15 by Letters Patent of the United States is:

1. The method of making a turned shoe which comprises sewing an upper to a sole having a flap formed at its heel end, the sewing extending forwardly of a line adjacent to the heel breast line, attaching the 20 inturned flap of a molded counter which is otherwise unattached to the shoe to the flap and completing the manufacture of the shoe.

2. The method of making a turned shoe which comprises sewing an upper to a sole having a flap formed at its heel end, the sewing extending forwardly of a line adjacent to the heel breast line, inserting beneath the flap the inturned 30 flap of a molded counter, fastening the flap to the sole but not to the sole and completing the manufacture of the shoe.

3. The method of making a turned shoe which comprises placing wrong side out upon a last an upper and a sole having a flap formed on its heel end, attaching the upper to the sole forwardly of a line adjacent to the heel breast line, inserting beneath the 40 flap the inturned margin of a molded counter, fastening the flap to the sole and completing the manufacture of the shoe.

4. The method of making a turned shoe which comprises placing wrong side out upon a last an assembled upper and lining and a sole having a flap formed on its heel end, attaching the upper and lining to the sole forwardly of a line adjacent to the heel breast line, inserting beneath the flap the 50 inturned margin of a molded counter, fastening the flap to the sole and completing the manufacture of the shoe.

5. The method of making a turned shoe which comprises placing wrong side out upon a last an upper and a sole having a flap formed on its heel end, sewing the upper to the sole, inserting beneath the flap the inturned margin of a molded counter, fastening the flap to the sole and completing the manufacture of the shoe.

6. The method of making a turned shoe which comprises placing wrong side out upon a last an upper and a sole having a slit in the heel end thereof, sewing the upper to the sole, inserting the inturned flap of a 65

molded counter in the slit, fastening the flap to the sole and completing the manufacture of the shoe.

7. The method of making a turned shoe which comprises placing wrong side out 70 upon a last an assembled upper and lining and a sole having a slit in the heel end thereof, sewing the upper and lining to the sole, inserting the inturned flap of a molded counter in the slit, fastening the 75 flap to the sole and completing the manufacture of the shoe.

8. The method of making a turned shoe which comprises sewing an upper to a sole having a flap at the heel end thereof, the 80 sewing taking place forwardly of a line adjacent to the heel breast line, inserting beneath the flap the inturned flap of a molded counter, fastening the counter to the flap but not to the sole and thereafter completing 85 the manufacture of the shoe.

9. The method of making a turned shoe which comprises sewing an upper to a sole having a flap at the heel end thereof, the 90 sewing taking place forwardly of a line adjacent to the heel breast line, placing in position a molded counter, the forward ends of the inturned flap of which are slitted, with the rear portion of the flap underlying the flap and the forward ends overlying the sole, fastening both the rear portion of the flap and the forward ends to the sole, and completing the manufacture of 95 the shoe.

10. The method of making a turned shoe which comprises placing wrong side out 100 upon a last an upper and a sole having a flap at the heel end thereof, sewing the upper to the sole, placing in position a molded counter, the forward ends of the inturned 105 flap of which are slitted, with the rear portion of the flap underlying the flap and the forward ends overlying it, fastening the counter to the sole, and completing the manufacture of the shoe.

11. The method of making a turned shoe which comprises placing wrong side out upon a last an upper and a sole having a flap at the heel end thereof, sewing the upper to the sole, placing in position a molded 110 counter, the forward ends of the inturned flap of which are slitted, with the rear portion of the flap underlying the flap and the forward ends overlying it, fastening the counter to the flap, turning the shoe 115 right side out, inserting a shank stiffener, fastening it to the sole and to the forward ends of the inturned flap of the counter, and completing the manufacture of the shoe.

12. The method of making a turned shoe which comprises placing wrong side out 120 upon a last an upper and a sole having a flap formed on its heel end, sewing the upper to the sole, placing in position a molded counter, the forward ends of the inturned 125

flange of which are slitted, with the rear portion of the flange underlying the flap and the forward ends overlying the sole, fastening the flap to the underlying portion 5 of the flange, fastening the forward overlying ends of the flange to the sole by means of a shank stiffener, and completing the manufacture of the shoe.

13. The method of making a turned shoe 10 which comprises sewing an upper to a sole having its heel end split to form a counter-reinforcing flap and a heel seat flap, the sewing taking place forwardly of a line adjacent to the heel breast line, inserting beneath the reinforcing flap the inturned flange of a molded counter, fastening the flange to the flap by fastening means located in the vicinity of the heel breast line, lasting the heel portion of the upper over 20 upon the bottom of the counter, laying the heel-seat flap and fastening it in place, and completing the manufacture of the shoe.

14. The method of making a turned shoe which comprises sewing an upper to a sole 25 having its heel end split to form a counter-reinforcing flap and a heel seat flap, the sewing taking place forwardly of a line adjacent to the heel breast line, inserting beneath the reinforcing flap the inturned flange of a molded counter, fastening the flange to the flap by fastening means located in the vicinity of the heel breast line, lasting the heel portion of the upper over 30 upon the bottom of the counter, laying the heel-seat flap and fastening it in place, fitting the heel-seat, and completing the manufacture of the shoe.

15. The method of making a turned shoe which comprises sewing an upper to a sole 40 having its heel end split to form a counter-reinforcing flap and a heel-seat flap, the sewing taking place forwardly of a line adjacent to the heel breast line, placing in position a molded counter having transverse 45 slits in its inturned flange near the forward ends thereof with the rear portion of the flange underlying the reinforcing flap and the forward ends overlying the sole, fastening both the underlying and overlying 50 portions of the flap to the sole, lasting the heel portion of the upper over upon the bottom of the counter, laying the heel-seat flap and fastening it in place, and completing the manufacture of the shoe.

16. The method of making a turned shoe which comprises placing wrong side out upon a last an assembled upper and lining and a sole having a flap formed on its heel end, sewing the upper and lining to the sole, 60 placing in position a molded counter, the forward ends of the inturned flange of which are slitted, with the rear portion of the flange underlying the flap and the forward ends overlying it, fastening together 65 the flap and the underlying portion of the

flange, pulling the last, turning the shoe right side out, putting the heel portion of the lining into place with its lower margin turned inwardly, inserting a shank stiffener which is coated with adhesive and is thereby attached to the forward ends of the counter flange which overlie the sole, and completing the manufacture of the shoe.

17. The method of making a turned shoe 70 which comprises sewing an upper to a sole having its heel end split to form a counter-reinforcing flap, a heel-seat flap and a heel-breast flap, the sewing taking place forwardly of a line adjacent to the heel breast line, fastening the inturned flange of a molded counter to the reinforcing flap, lifting up the heel-seat and heel-breast flaps, and lasting the heel end of the upper, laying the heel-seat flap and fastening it to the reinforcing flap, fitting the heel-seat and completing the shoe, including attaching the heel and laying the third flap on the heel breast thereof.

18. As an article of manufacture, a turned shoe 75 having a slit in the heel end of its sole, a molded counter the inturned flange of which lies in the slit, an upper the lower margin of the heel portion of which is in contact with the under side of the inturned flange of the counter, and a lining the lower margin of which is in contact with the sole at a locality above the inturned flange.

19. As an article of manufacture, a turned shoe having a flap formed at the heel end 80 of its sole, a molded counter the inturned flange of which is located beneath the flap and fastened thereto, an upper, the lower margin of the heel portion of which is lasted over and attached to the counter, and a lining the inturned lower margin of the heel portion of which rests upon the flap.

20. As an article of manufacture, a turned shoe having formed at the heel end of its sole a counter-reinforcing flap and a heel-seat flap, a molded counter the inturned flange of which extends beneath the reinforcing flap, an upper the lower margin of the heel portion of which is lasted over the counter, a lining the inturned lower margin of the heel portion of which rests upon the flap, and a heel, the upper face of which contacts with the heel-seat flap.

21. The method of making a molded counter turned shoe in such manner as to 110 do away with the use of a separate counter-reinforcing member which comprises providing a component member of the shoe with a counter-reinforcing flap, fastening the inturned flange of a molded counter to the flap and thereafter completing the manufacture of the shoe including laying the inturned lower margin of the lining upon the upper face of the flap.

22. The method of making a molded counter turned shoe in such manner as to 115

70

75

do away with the use of a separate counter-reinforcing member which comprises splitting a component member of the shoe to provide a counter-reinforcing portion, fastening the inturned flange of a molded counter to the portion, and thereafter completing the manufacture of the shoe, including laying the inturned lower margin of the lining upon the upper face of the portion.

23. The method of making a molded counter turned shoe in such manner as to do away with the use of a separate counter-reinforcing member which comprises providing a counter-reinforcing flap on the heel end of a component member of the shoe, fastening the inturned flange of a molded counter to the flap before the shoe is turned right side out and thereafter turning the shoe and completing its manufacture including laying the inturned lower margin of the lining on the upper side of the flap to which the counter is attached.

24. As an article of manufacture a turned shoe having formed at the heel end of a component part thereof, a counter-reinforcing flap to take the place of the usual sepa-

rate counter-reinforcing member, a molded counter the inturned flange of which lies below and is fastened to the flap, and a lining the lower inturned margin of which lies upon the flap.

25. As an article of manufacture a turned shoe having a molded counter and a counter-reinforcing flap having a contour corresponding to the contour of the inner wall of the counter just above the inturned flange thereof, said flap being fastened to said flange, constituting a part reduced in thickness of the heel end of a component member of the shoe, and having a contour coinciding with the contour of the heel end of said member.

26. As an article of manufacture a turned shoe the inturned flange of the molded counter of which is received between two flaps carried at the heel end of a component member of the shoe, the inturned lower margin of the heel portion of the lining of the shoe lying upon one of said flaps.

In testimony whereof I have signed my name to this specification.

HARRY L. YEATON.
